US0D1065736S

(12) **United States Design Patent** (10) **Patent No.:** **US D1,065,736 S**
(45) **Date of Patent:** **** Mar. 4, 2025**

(54) **SUCTION HEAD FOR VACUUM CLEANER**

(71) Applicant: **Iris Ohyama Inc.**, Sendai (JP)

(72) Inventor: **Takuya Abe**, Kakuda (JP)

(73) Assignee: **Iris Ohyama Inc.**, Sendai (JP)

(**) Term: **15 Years**

(21) Appl. No.: **29/869,393**

(22) Filed: **Dec. 29, 2022**

(30) **Foreign Application Priority Data**

Jul. 5, 2022 (JP) ..... 2022-014467 D

(51) **LOC (15) Cl.** **15-05**

(52) **U.S. Cl.**

USPC **D32/32**

(57) **CLAIM**

The ornamental design for a suction head for vacuum cleaner, as shown and described.

DESCRIPTION

FIG. 1 is a front, top and right-side perspective view of a suction head for vacuum cleaner showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof; and,

FIG. 8 is a perspective view shown in a state of use.

The broken lines shown represent portions of the suction head for vacuum cleaner and form no part of the claimed design.

1 Claim, 8 Drawing Sheets
